UNITED STATES PATENT OFFICE.

WALTER CHAUNCEY CAMP, OF NEW YORK, N. Y., ASSIGNOR TO THE NEW HAVEN CLOCK COMPANY, OF NEW HAVEN, CONNECTICUT.

DESIGN FOR A CLOCK-CASE.

SPECIFICATION forming part of Design No. 16,912, dated September 28, 1886.

Application filed May 25, 1886. Serial No. 203,240. Term of patent 3½ years.

To all whom it may concern:

Be it known that I, WALTER CHAUNCEY CAMP, residing at New York, in the county of New York and State of New York, have invented a certain new and original Design for Clock-Cases; and I do declare the following to be a full, clear, and exact description of the same, reference being had to the accompanying drawings, which form a part of this specification.

Figure 1 is a view in front elevation of my newly-designed clock-case. Fig. 2 is a side view of the same.

The leading feature of my design consists of a case spherical in general contour, and having spikes distributed over its outer surface. The said case is shown in the drawings at A, and the spikes are indicated by F, the latter having ornamentally-beaded shanks and conical points. The sphere, of which the case A is the major part, is cut by the plane B, the said case being specifically of the contour of a segment of a sphere.

E indicates a minor segment of a sphere,

which is applied to the case A, with an intervening band or offset, D.

What I claim is—

1. The design for a clock-case herein shown and described, the same consisting of a case spherical in general contour, and having spikes distributed over its outer face.

2. The design for a clock-case herein shown and described, the same consisting of a case having the contour of the segment of a sphere, with spikes distributed over its outer face.

3. The design for a clock-case herein shown and described, the same consisting of a case having the contour of the segment of a sphere, with spikes distributed over its outer face and having the segment E.

In testimony whereof I have signed this specification in the presence of two subscribing witnesses.

WALTER CHAUNCEY CAMP.
